CLAIM

The ornamental design for a periscope playground panel, as shown and described.

DESCRIPTION

FIG. 1 is a top right front perspective view of a periscope playground panel showing our new design;
 FIG. 2 is a front elevational view thereof;
 FIG. 3 is a top plan view thereof;
 FIG. 4 is a bottom plan view thereof;
 FIG. 5 is a right side elevational view thereof; the left side elevational view being a mirror image; and,
 FIG. 6 is a rear elevational view thereof.
